UNITED STATES PATENT OFFICE.

LAWRENCE R. BLACKMORE, OF NEWARK, NEW JERSEY.

DESIGN FOR A RADIATOR.

SPECIFICATION forming part of Design No. 22,402, dated May 2, 1893.

Application filed March 9, 1893. Serial No. 465,352. Term of patent 7 years.

To all whom it may concern:

Be it known that I, LAWRENCE R. BLACKMORE, a citizen of the United States, residing at Newark, Essex county, New Jersey, have invented a certain new and original Design for Heating-Radiators, fully described and represented in the following specification and the accompanying drawing, forming a part of the same.

10 The annexed drawing illustrates a radiator embodying my design. The radiator exhibits an appearance of two columns *a, a'*, joined at their ends by loops *b* and crossed twice intermediate to their ends. The crossing of the 15 columns (lettered *c* in the drawing) divides the upper and lower portions of the same into four panel-like portions which are ornamented by four different patterns in relief. The pattern in the upper portion of column *a* represents a bunch of Easter lilies, while the pattern in the lower portion represents a twig with large serrated leaves and blossoms. The 20 pattern in the upper portion of column *a'* rep-

resents a twig with ovate tre-foil leaves and several blossoms; and the pattern in the lower portion of column *a'* represents a group of cat-tails and rushes.

The essential feature of the design is the radiator having two columns joined at their ends by loops and crossed twice intermediate to their ends; the columns above and below the crossings constituting four panel divisions provided each with a different ornamental pattern in relief.

Having thus set forth the design, what I 35 claim is—

The design for a radiator, substantially as herein set forth.

In testimony whereof I have hereunto set my hand in the presence of two subscribing 40 witnesses.

LAWRENCE R. BLACKMORE.
